(57) CLAIM

The ornamental design for a tea light candle holder for a bottle, as shown and described.

DESCRIPTION

FIG. 1 is a top perspective view showing the tea light candle holder of the invention, with a tea light candle placed in the holder;

FIG. 2 is view similar to FIG. 1 without the tea light candle in the tea light candle holder;

FIG. 3 is a side elevation of the tea light candle holder of the invention, the candle holder being uniform in appearance from all sides;

FIG. 4 is a top view of the tea light candle holder of the invention; and,

FIG. 5 is a bottom view of the tea light candle holder of the invention.

The broken line showing of a tea light candle in FIG. 1 is for illustrative purposes only and forms no part of the claimed design.
